UNITED STATES PATENT OFFICE.

RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOEMAKING-MACHINE.

1,119,046.

Specification of Letters Patent.

Patented Dec. 1, 1914.

Application filed November 27, 1911. Serial No. 662,598.

To all whom it may concern:

Be it known that I, RALPH C. SIMMONS, a citizen of the United States, residing at Beverly, in the county of Essex and State of 5 Massachusetts, have invented certain Improvements in Shoemaking-Machines, of which the following description, in connection with the accompanying drawings, is a specification, like reference characters on 10 the drawings indicating like parts in the several figures.

This invention relates to machines for operating upon boots and shoes, and is herein shown and described, by way of example, as 15 embodied in machines for removing the surplus material from the forward face of the heels of boots and shoes in the operation known as breasting.

In the process of making boots and shoes, 20 it is customary, after the shoe has been lasted and the outsole attached and rough rounded, to nail on the heel in the rough condition with nails which are allowed to project somewhat from the outer face of the 25 rough heel. A carefully shaped top lift is then spanked upon the projecting nails and serves as a guide to indicate the depth of cut to be removed by the rotary cutter by which the convex portion of the heel is trimmed. 30 The surplus material on the front or breast face is removed in a separate operation which is usually performed by a reciprocating breasting knife which may be either flat, for breasting the heel straight, or 35 gouge-shaped, so arranged as to render the breast face of the heel concave. The breasting cut is often made in a plane perpendicular to the longitudinal median line of the heel and in this case the breast edge of the 40 top lift may be used to indicate the initial position for the knife in making the breasting cut, the edge of the knife being positioned in front of and against the breast edge of the top lift. As the breast edge of 45 the top lift is usually straight, however, this could be done only in the case of a flat knife. If a straight-edged top lift is used on heels which are to be breasted with a curved or gouge-shaped knife, only the corners serve 50 as position indicating means for the knife and an intermediate part of the lift is removed. It is, moreover, common practice to 55 breast heels with the plane of the breast face at an angle of a few degrees to the longitudinal median line of the heel, the in-

clination being in one direction for right shoes and in the other direction for left shoes. In this practice it will be apparent that only the right or the left corner of the top lift can be used as a guide and that this 60 corner indicates merely the forward limiting position of the plane of the breasting cut. It is desirable, therefore, in the operation of breasting heels rights and lefts, 65 i. e. as last above described, to use a gage which will contact with the breast edge of the top lift and indicate the proper angular position of the heel relatively to the knife for securing the proper angle at the breast to the median line for either rights or lefts. 70

It is the object of this invention to provide an improved gage for this purpose which may be conveniently arranged upon the breasting machine and will enable the operator easily and accurately to position 75 the heel at the proper angle to the breasting knife.

An important feature of my invention is the provision of an improved breasting gage arranged for oscillation about an axis approximately perpendicular to the tread face of the heel and provided with stops for limiting the amount of oscillation to equal angles upon opposite sides of a line parallel to the edge of the knife. 80

It is also a notable feature of the invention that the stops for limiting the pivotal movement of the gage are equally and oppositely adjustable simultaneously so that the swing of a right heel relatively to the knife 85 is always equal and opposite to that of a left heel.

Breasting machines of the type to which my invention is particularly adapted for application are provided with a presser plate 90 which is pressed against the tread face of the heel to clamp it in position prior to the cutting stroke of the knife.

As a feature of my invention the gage is so mounted as to be maintained in constant 100 vertical relation to the presser plate and hence in proper position to engage the breast face of a top lift pressed against the plate. This result is attained by pivoting the arm carrying the gage at a point in lateral alignment with the forepart of the shoe and providing means for resiliently swinging the arm toward the presser plate, a stop being provided on the arm for contact with means attached to the plate to limit the 105 110

movement of the arm relatively to the plate in one direction.

By mounting the gage carrying arm as above indicated, it may be moved toward the shoe against the resilient means tending to move it against the presser plate, and it is a feature of my invention that the arm is arranged to be engaged by the bunter of the breasting machine and moved down against the shoe shank. To permit this movement, however, the breast gage must be drawn away from the heel breast after having performed its positioning function, in order to clear the surplus material about to be removed from the breast face of the heel. Incidentally, also, this movement draws the gage away from the path of the breasting knife. The feature of having the bunter engage the arm and force that against the shoe instead of coming directly in contact with the shoe itself is of importance for the reason that as the arm presents a larger area for contact with the shank than does the bunter, there is less danger of the shank being marred by the action of the bunter in arresting the movement of the knife.

As a further feature of the invention, the support of the gage carrying arm is arranged for adjustment in a direction at right angles to the plane of the knife and hence the position of the gage relatively to the knife may be adjusted to determine the amount of material to be removed from the heel, and, further, the gage carrying arm is arranged to be swung into inoperative position at the will of the operator, so that the machine may be used without the gage if desired.

Referring now to the drawings which represent a machine provided with an illustrative embodiment of my invention; Figure 1 is a side view of the operative portion of the machine; Fig. 2 is a perspective view of the same; Fig. 3 is a sectional view, partly in plan, taken on the line 3—3 of Fig. 1.

Referring particularly to Fig. 1, the operative parts of the machine are supported upon a standard or column 2 and comprise a knife slide 4, an actuating slide 6, (Fig. 2), a presser plate 40 and heel locating mechanism to be subsequently fully described. The knife slide 4 carries projecting to one side thereof a knife carrier 10 having the cheek portions 12. Engaging behind the cheek portions 12 is a plate 14 carrying screws 16 and behind the plate 14 is a second plate 20. Between the plates 14 and 20 is located the shank portion of the knife 22. As the screws 16 are tightened the shank of the knife is forced against the back plate 20 while the forward plate 14 is forced against the inner faces of the cheek members 12 and the knife is thus firmly clamped 65 in place.

To furnish an abutment for the knife an overhanging portion 24 of the knife carrier has screws 26 threaded therethrough and so located that they engage the upper end of the shank of the knife. Lock nuts 28 are provided to hold the screws 26 in adjusted position. The knife slide 4 is actuated in the usual manner, means being set into operation by a treadle to reciprocate the actuating slide 6, which is connected with the knife slide, to reciprocate the knife to perform the breasting operation.

It is necessary that the cutting action of the knife be arrested when the shank portion of the shoe is reached and a usual stop mechanism is provided for disconnecting the knife slide from the actuating slide at the proper moment in the knife stroke. This is effected by the contact of the bunter 30 with the shoe shank, the bunter acting through the lever 32 to actuate mechanism for disconnecting the knife slide from the actuating slide.

The machine is provided with the usual presser plate 40 which is arranged to be depressed upon the tread face of the heel by means of a treadle acting through the rod 42 and spring 44 against the lever 46 which is pivoted at one end to the machine frame at 48 and at the other is connected by toggle links to the slide 50 carrying the presser plate at its lower end. Pressure upon the treadle pulls the rod 42 downwardly and acts through the spring 44 to resiliently depress the presser plate against the tread face of the heel. In order conveniently to limit the range of movement of the presser plate upwardly, a bracket 52 is attached to the machine frame and arranged to project inwardly over the lever 46 and a screw 54 is threaded through the bracket into engagement with the lever 46. By adjusting the screw 54 the upper limit of movement of the presser plate may be changed.

The presser plate 40 is pivoted to the lower end of the slide 50 upon the pin 56 and is held in its normal substantially horizontal position by means of a spring 58 attached to the plate at a point forward of the pivot 56 and connected to a handle 60 by which the toggle links connecting the lever 56 with the slide 50 are operated. The spring therefore acts to hold the presser plate up in its operative position and to hold the toggle lever 60 down with the toggles in a straightened position. By raising the lever 60 and breaking the toggle connecting the slide 50 with its operating lever the presser plate may be moved upwardly to a position behind the knife and the plate may then be conveniently adjusted longitudinally by positioning it against the back of the knife and clamping it. Upon release of the lever the plate drops back into its normal 130

position beneath the knife, and, the toggle being held straight by the weight of the slide 50 and by the spring 58, the plate may be actuated by power transmitted from the 5 lever 46 through the toggle.

The slide 50 is mounted for vertical reciprocation in ways formed in a bracket 62 on the frame of the machine. Extending rearwardly from the slide 50 is a projection 10 64 and a curved abutment 66, the function of which will appear later, is secured pivotally to the pin 56 and is attached to the projection 64 by means of an eccentric pin 68 by rotation of which the vertical position 15 of the forward end of the abutment may be adjusted, as will be readily understood.

The mechanism for locating the position of the heel of the shoe relatively to the breasting knife, which forms an important 20 feature of the present invention, comprises a gage 90 which is supported by a casting 70 rigidly secured to the top of the machine frame. A hanger 72 is mounted for sliding movement in a horizontal direction upon the 25 casting 70 and is normally adjustably maintained in the inward position of its movement by a spring 74 with a limiting stop screw 76 carried thereby in contact with the casting 70 and fixing the inner limit of its 30 movement. To reciprocate the hanger 72 so as to remove the heel locating device from contact with the rough portion of the heel to be removed by the breasting operation, as well as to remove it from the path of the 35 knife, a roll 78 is mounted on the upper portion of the hanger 72 in the path of a member 80 secured at 82 to the knife slide and having the cam surface 84 for contact with the roll 78. As the knife slide descends the 40 cam surface 84 engages the roll 78 and forces the hanger 72 outwardly against the tension of the spring 74, thereby carrying the heel locating device mounted upon the hanger 72 out of the path of the knife.

45 Means is provided for holding the gage in retracted position, when desired, and as shown this means comprises a pawl 73 which is normally held by gravity in position to engage suitably arranged teeth 71 formed on the upper face of the hanger 72. When the gage is withdrawn from operative 50 position, the pawl 73, when in the position shown, will engage the teeth 71 and hold the gage out of the way until it is desired to use it again. When the gage is desired, the 55 pawl 73 is raised by the handle 75 and thrown backward against a portion of the machine, and the gage is permitted to resume its operative position under the impulsion of the spring 74.

60 The heel locating device comprises a gage member 90 which, as shown, is adapted to contact throughout the full lateral extent of the breast edge of the top lift and is preferably so thin that it engages the top lift only

of the heel. The member 90 is pivoted at 92 to an inwardly projecting portion 95 of an arm 94 and the other end of the member 90 is formed to engage alternatively the limiting stops 96, 97, which are slidably mounted in the arm 94 and are arranged to be moved equally and oppositely toward and from each other by means of a right and left hand screw carrying the thumb head 100. By this means the extent of oscillation 70 of the breast engaging member 90 about the pivot 92 may be adjusted to effect variations in the inclination of the heel breasts 75 of right and left hand shoes to the longitudinal median line of the heel. The vertical position of the gage 90 relatively to the presser plate 40 is determined by the abutment 66, already referred to, with which a block 102 secured at 104 (Fig. 3) to the arm 94 normally contacts. The vertical position 80 of the gage 90 relatively to the presser plate may be adjusted by means of the eccentric pin 68, it being desirable to locate the upper face of the gage 90 just below the lower face of the presser plate 40. The arm 90 85 is provided with an inwardly projecting portion 106 formed to interlock at 108 with a member 110 pivoted at 112 and guided for movement about said pivot by lugs 114 arranged on each side of a guide 116 projecting from the hanger 72. The pivot 112 of the member 110 passes through a block 120 which has a stem 122, Fig. 1, mounted for 90 sliding movement in a bearing in the lower end of the hanger 72. A screw 124 having 95 an operating head 126 is held from longitudinal movement in the lower end of the hanger 72 by the cap plate 128 and at its inner end is threaded into the stem 122 of the member 120.

100 By operating the head 126 it will be seen that the breast gage 90, together with the arm 94 and connected parts, may be moved horizontally and the breast gage 90 thereby adjusted toward and from the heel to vary 105 the amount of material removed from the breast end thereof. The block 102 is normally held resiliently against the abutment 66 and to effect this the member 110, Fig. 1, is provided with a stem 130 extending 110 through an opening in the hanger 72 and having thereon a compression spring 132 abutting at one end against a collar 134 on the hanger and at the other against a collar 136 secured upon the outer end of the stem 115 130. It will be seen that the spring tends to turn and hold the upper end of the member 110 outwardly about the pivot 112 and that the arm 94 being normally rigid with the member 110 is thereby held upwardly 120 against the abutment 66.

125 The shoe to be operated upon is placed upon the jack 140 with the toe portion resting upon the toe rest 142. The treadle referred to is now depressed to lower the 130

presser plate against the tread face of the heel. During this movement of the presser plate the abutment 66 is of course carried down and by contact with the block 102 5 swings the arm 94 about the pivot 112, compressing the spring 132. When the presser plate has reached contacting position with the tread face of the heel, the breast gage 90 will be in position just in front of the 10 breast edge of the top lift. The shoe is now drawn forwardly, bringing the breast edge of the top lift into continuous engagement with the gage 90 and the shoe is then swung to right or left, as the case may be, 15 while still maintaining its continuous engagement until the outer end of the gage member 90 contacts with one or the other of the members 96 or 97, according as a right or left heel is being breasted. The 20 shoe is now definitely positioned relatively to the knife, and upon further depression of the treadle the clutch is thrown in and the knife actuated to perform the breasting cut. As the knife slide starts upon its 25 downward movement the cam 80 contacts with the roll 78 and the hanger 72 is forced outwardly, carrying with it the gage 90 and connected mechanism. The gage 90 is thus drawn out of the way of the material of the 30 heel which is to be removed by the breasting cut of the knife and also out of line with the cutting edge of the knife. As the knife descends farther, the bunter 30 comes into contact with the inwardly projecting 35 portion 95 of the arm 94 and communicates its downward movement thereto, further compressing the spring 132 until finally the portion 95 contacts with the shank portion of the shoe and further movement of the 40 bunter 30 is arrested. As the movement of the bunter stops, the arm 32 is moved relatively upward, and the mechanism for disconnecting the knife slide 4 from the actuating slide 6 is operated, and further cutting 45 action of the knife prevented; it being understood, of course, that the stop 30 has been so adjusted that the knife will cut down to but not into the shank portion of the sole.

50 It may be desirable at times to swing the arm 94 out of its operative position and for this purpose the interlocking engagement at 108 of the portions 106 and 110 is provided. By drawing the portion 106 outwardly 55 against a suitably arranged spring, not shown, it is drawn out of interlocking engagement with the part 110 and may then be swung downwardly upon the axis of the portion 106 into an inoperative position.

60 Having described my invention, what I claim as new and desire to secure by Letters Patent of the United States is:—

1. In a heel breasting machine the combination of a reciprocating knife, a gage 65 adapted to engage the breast of a top lift

and mounted for movement about a pivot located substantially perpendicular to the tread face of the heel and substantially in the longitudinal median line thereof, means for normally holding the gage in operative 70 position beneath the knife, and means for moving the gage out of the path of the knife.

2. A heel breasting machine, having in combination, a knife, a presser plate, a gage support mounted independently of the presser plate for sliding movement at an angle to the path of the knife, and a gage on said support arranged to engage the breast of the heel, the support being resiliently held up against the presser plate to 75 locate the gage vertically.

3. A heel breasting machine, having, in combination, a knife, a support mounted for sliding movement at an angle to the path of the knife, an arm pivoted on said support, and a gage thereon, said arm being adapted normally to present the gage to the heel breast and to be swung downwardly 80 into inoperative position when not in use.

4. In a heel breasting machine the combination with a reciprocating breasting knife, means for actuating the knife, a bunter moving with the knife and arranged to disconnect the knife from its actuating 85 means to arrest the cutting action thereof upon arrestment of the movement of the bunter, and means arranged between the shoe and the bunter and having a larger surface in contact with the shoe than the bunter to receive and distribute the impact 90 of the bunter and prevent marring of the shoe.

5. In a heel breasting machine the combination with a reciprocating breasting 105 knife, of a bunter moving with the knife arranged to arrest the cutting action thereof upon arrestment of the movement of the bunter, a breast gage, and an arm carrying the gage and resiliently held above the shoe 110 bottom in the path of said bunter whereby the arm is depressed by impact of the bunter into contact with the shoe to arrest the knife.

6. In a heel breasting machine the combination with a reciprocating breasting 115 knife, a bunter moving therewith and adapted when its movement is stopped to arrest the action of the knife, a gage for positioning the heel by contact with the breast thereof, and a support for said gage arranged in the path of the bunter and adapted to be forced against the shoe to 120 stop the bunter and arrest the action of the knife.

7. In a heel breasting machine the combination with a reciprocating breasting knife, a bunter moving therewith and adapted when its movement is stopped to arrest the action of the knife, of a gage arranged to 130

contact with the breast edge of the top lift of a shoe, an arm carrying the gage and adapted to be depressed against the shoe bottom, and means for withdrawing the gage from contact with the heel upon the descent of the knife and for bringing the gage into the path of the bunter for depression thereby against the shoe.

8. In a machine of the class described, the combination with breasting means, of a pivoted gage 90, an arm 94 carrying the gage, and opposed stops 96, 97 arranged to engage opposite sides of the same end of the gage for limiting the movement of the gage relatively to the arm.

9. In a heel breasting machine, the combination with a reciprocating knife and a presser plate, of a hanger 72, an arm 94 carried by the hanger, a spring 132 for normally holding the arm in position beneath the presser plate, a swinging gage 90 on said arm, and adjustable means on said arm for limiting the swing of said gage.

In testimony whereof I have signed my name to this specification in the presence of two subscribing witnesses.

RALPH C. SIMMONS.
